UNITED STATES PATENT OFFICE.

CLAUDE THEODORE SIEBS, OF RIVERSIDE, ILLINOIS, ASSIGNOR TO WESTERN ELECTRIC COMPANY, INCORPORATED, OF NEW YORK, N. Y., A CORPORATION OF NEW YORK.

HOISTING APPARATUS.

Application filed July 11, 1925. Serial No. 42,883.

This invention relates to hoisting apparatus and more particularly to electrically operated locomotive cranes and the like.

When operating hoisting apparatus, especially electrically operated cranes of a relatively high center of gravity design and having a long boom radius, the stability of the crane under certain working conditions is sometimes reduced to a figure which necessitates limiting the boom radius used under maximum load conditions or limiting the load carried under maximum boom radius conditions. Especially in the operation of hoisting apparatus of the locomotive type, such as is movably mounted on rails, the possibility of overbalancing due to excessive loading with the boom operating in certain zones, sometimes renders its operation very unsafe unless the load or boom radius is limited to a predetermined safe figure in those zones.

The primary object of this invention is the provision, in hoisting apparatus of the above character, of mechanism for insuring its safe operation at substantially full capacity throughout its entire range of action.

One embodiment of the invention may comprise an electrically operated locomotive crane, such as is movably mounted on rails, the operation of which may be controlled by two electrical limit switches connected in parallel with one another in the operating circuit. A suitable tension device mounted in the boom lift operates one of the limit switches when the product of the weight lifted multiplied by the boom radius equals some predetermined figure. The other limit switch is operated by a suitable platform cam in accordance with the angular position of the boom with respect to the rails. An additional inching push button switch may be provided to enable the operator to inch back into a safe zone should he pull out both limit switches by excessive loading.

Other features of the invention will become apparent in the following detail description, reference being had to the accompanying drawings, wherein

Fig. 1 is a schematic side view of an electrically operated locomotive crane embodying the features of the present invention;

Fig. 2 is a schematic fragmentary plan view thereof;

Figs. 3 and 4 are enlarged detail views of

one form of tension device that may be employed in the boom lift for actuating one of the limit switches;

Fig. 5 is a detail section taken on the line 5—5 of Fig. 1; and

Fig. 6 shows a diagram of a portion of an electrical operating circuit which is suitably adapted for use in connection with the present embodiment of the invention.

Referring now to the drawings in detail and particularly to Fig. 1 thereof, the reference numeral 10 indicates, generally, a truck which is carried upon a plurality of wheels 11 whereby it is adapted to travel along a standard gauge track 12. Supported by the truck 10 is a platform 14 upon which is rotatably carried the usual operator's cab 15. The cab 15 is supported on a plurality of rollers 16 which travel on the upper surface of the platform 14 when the cab 15 is rotated. Rigidly supported by the frame of the cab is a suitable structural steel mast 18, to the lower end of which is pivotally connected an elongated structural steel boom 19.

Mounted in the cab 15 is a suitable winding drum 20 having attached thereto and adapted to receive a cable 22 for raising and lowering a hoist block 23 carried at the outer end or head of the boom 19. One end of the cable 22 is suitably attached to the outer end of the boom, whence it extends outwardly and around a sheave 24 of the hoist block 23, then upwardly and over a sheave 25 carried at the outer end of the boom 19 and then around the drum 20 to which the free end of the cable is suitably attached.

The construction thus far described is well known in the art and since it forms no part of this invention, it is believed that a further illustration and detailed description thereof is unnecessary.

In cranes of this type it is desirable to employ mechanism for automatically limiting the tension in the boom lift while working in certain predetermined areas, thereby preventing overbalancing of the apparatus due to excessive loading in those areas. This mechanism may comprise a tension device 30 (Figs. 3 and 4) which operates a suitable limit switch 31 controlling an electrical operating circuit 32 (Fig. 6). The device 30 comprises a substantially cup shaped casting 34 having a central aperture

35 in its base 36 within which is slidably journaled a bar 37. Attached to one end of the bar 37 at right angles thereto is a disk member 38 which fits loosely within the casting 34. The opposite end 39 of the bar 37 extends outwardly beyond the base 36 and has attached at right angles thereto a bar 40 which is adapted to operate the limit switch 31 by engaging a pivoted arm 41 thereof. Disposed between the disk member 38 and the inner face of the base 36 are a plurality of compression springs 42, 42 which normally urge the bar 37 inwardly, in which position the bar 40 is disengaged from the arm 41 and the limit switch 31 is closed thereby maintaining the operating circuit 32 closed. The device 30 is designed so that it automatically operates the limit switch 31 as soon as the tension in the boom lift reaches some predetermined safe figure.

Formed on the casting 34 at the end opposite the base 36 are a pair of lugs 45, 45 having apertures 46, 46 by means of which the tension device 30 is pivotally secured to a lug 48 rigidly secured to the top of the mast 18. Pivotally connected, at one end, to the end 39 of the bar 37 is a bar 50 which carries at its opposite end a rotatable sheave 51. A suitable cable 52 is fastened to the bar 50 as indicated at 53 (Fig. 1) whence it passes around one of a pair of rotatable sheaves 54, 54 carried by a sheave block 55, then around the sheave 51, and back around the second sheave 54, whence it is taken up by a suitable winding drum (not shown) mounted in the cab 15. Fastened at one end to the sheave block 55 is a suitable cable 57 which is fastened at its opposite end to the head of the boom 19, as indicated at 58.

40 Referring to Fig. 2, the dotted lines 100 and 101, intersecting at the center or theoretical pivot point of the crane, divide the working area thereof our four working zones indicated by letters A, B, C and D, respectively. It is obvious that the crane may safely handle heavier loads in the areas A and B with the boom parallel or at a small angle to the rails than in the areas C and D when the boom is at right angles or at a comparatively large angle to the rails. It is therefore necessary that the tension device 30 be designed so as to actuate the limit switch 31 when the tension in the boom lift reaches a predetermined limit in accordance with the safe working capacity of the crane under operating conditions in the areas C and D. Such an arrangement by itself would, however, unnecessarily limit the permissible loading of the crane in the areas A and B wherein the crane may be operated safely at a greater capacity than in the areas C and D.

60 An important feature of this invention is the provision of mechanism whereby the crane may be operated at substantially full

capacity in those areas wherein it is safe to permit loading to full capacity. This mechanism comprises a suitable limit switch 60 connected in the operating circuit 32 in parallel with the limit switch 31 and operated by mechanism, hereinafter described, to control the operating circuit 32 in accordance with the angular position of the boom in a horizontal plane relative to the rails.

As shown in Fig. 5, the platform 14 is substantially circular in construction, having a pair of diametrically opposed portions 61 of larger radius than a pair of similarly opposed portions 62. The peripheral surfaces of these portions constitute a continuous cam surface which is constantly engaged by a roller 63 rotatably carried at one end of a bar 64. The bar 64 is slidably supported in bearings 65 and 66 formed at opposite ends of a housing 67, which housing is suitably secured on the under side of the cab 15. Formed on the bar 64 intermediate its ends are a plurality of lugs 68, 68 which project outwardly substantially at right angles to the bar. Interposed between the lugs 68 and one end 69 of the housing 67 are a plurality of compression springs 70 which normally urge the bar 64 outwardly towards the platform 14, thereby insuring that the roller 63 is constantly in engagement with the periphery thereof.

The end of the bar 64 projecting through the bearing 66 is adapted to open the limit switch 60 by engaging a pivoted arm 72 thereof (Fig. 5) when the roller 63 engages either of the sections 61 of the platform 14. The platform 14 is so disposed with respect to the rails 12 that the roller 63 engages one of the sections 61 thereof when the boom is operating in the zones C and D, the sections 62 of the platform being engaged by the roller when the boom is operated in the zones A and B.

The operation of the above described mechanism is as follows: The tension device 30 is so designed that it automatically opens the limit switch 31 when the tension in the boom lift reaches some predetermined figure, which is determined by the safe loading capacity of the crane with the boom operating in the zones C and D. With the boom operating in the zones A and B the crane is permitted to handle heavier loads to the extent of its full capacity since the operating circuit is maintained closed through the limit switch 60 which is controlled by the angular position of the boom with respect to the rails. As the boom moves into either of the zones C and D the limit switch 60 is automatically opened through the platform cam 14, as hereinbefore described. However, since the limit switches 31 and 60 are connected in parallel with one another, the operating circuit is maintained closed through either or both switches so that if the tension

device 30 opens the limit switch 31 when the crane is operating in either of the areas A or B, the operating circuit will be maintained through the platform cam switch 60. Alternatively in the areas C and D the platform cam switch is open which places the entire control of the operating circuit in the switch 31. A non-locking push button switch 75 is connected in the operating circuit 32 in parallel with the limit switches 31 and 60 and serves as a means whereby the operator may move the boom into a safe zone should the limit switch 31 be opened by excessive loading in the zones C and D.

Although the invention, as herein illustrated and described, is particularly well adapted for use in connection with electrically operated locomotive cranes, it should be understood that it is not limited thereto and that modifications may be made without departing from the scope of the invention as defined in the appended claims.

What is claimed is:

1. In a crane, the combination with a rotatable boom, of means including a cam member rotated by the boom and means actuated thereby for controlling the safe loading capacity of the crane.
2. In a crane, the combination with a rotatable boom and lifting means therefor, of means responsive to the tension in said lifting means for controlling the safe loading capacity of the crane, and means controlled by the rotation of the boom for con-

trolling the effectiveness of the tension responsive means.

3. In a crane, the combination with a rotatable boom and means including an electrical circuit for operating the boom, of means controlled by the load carried by the boom for controlling said circuit, and means operated by the rotation of the boom for controlling the effectiveness of said circuit controlling means.

4. In a crane, the combination with a rotatable boom and means including an electrical circuit for operating the boom, of a plurality of means cooperating to control said circuit, means controlled by the load carried by the boom for operating one of said circuit controlling means, and means controlled by the rotation of the boom for operating another of said circuit controlling means.

5. In a crane, the combination with a rotatable boom and means including an electrical circuit for operating the boom, of a plurality of switches connected in parallel with one another and cooperating to control said operating circuit, a tension device actuated by the load carried by the boom for controlling one of said circuit controlling switches, and a cam rotatable with the boom for controlling another of said circuit controlling switches.

In witness whereof, I hereunto subscribe my name this third day of July, A. D., 1925.

CLAUDE THEODORE SIEBS.
